(57) **CLAIM**

The ornamental design for a component of a grilling accessory, as shown and described.

DESCRIPTION

FIG. 1 is a perspective view of a first cover component of a grilling accessory according to our new design;

FIG. 2 is a perspective view of a second cover component of a grilling accessory according to our new design;

FIG. 3 is a top view of the component of FIG. 1;

FIG. 4 is a top view of the component of FIG. 2;

FIG. 5 is a front elevation view of the component of FIG. 1, the rear side elevation view being identical thereto; and,

FIG. 6 is a right side elevation view of the component of FIG. 1, the left side elevation view being identical thereto; and FIG. 6 is also a front side elevation view of the component of FIG. 2; the rear, left and right side elevation views being identical thereto.

The claim is only made toward those ornamental features common between the first and second components, the quantity of segments thereby forming no part of the claimed design. Additionally, the wire-mesh construction in broken lines is shown for environmental purposes only and forms no part of the claimed design.
